DEVELOPING RACK

Herman Millman, New York, N. Y.

Application March 17, 1944, Serial No. 526,890

5 Claims. (Cl. 95—100)

1

This invention relates to new and useful improvements in a developing rack for direct positive photographs and the like.

More particularly, the invention proposes an improved rack characterized by a frame-like member having a plurality of groove-like passages in which strips of photographs and the like may be supported. It is proposed to provide means for closing one end of said member for holding said strips of photograph in position. It is further proposed to mount a handle on the other end of the member by which the developing rack may be dipped into developing fluids.

The invention proposes various modified forms distinguishing from each other in the details of construction of the frame-like member, in the arrangement and construction of the groove-like passages, and in the arrangement and construction of the means for closing one of the ends of said frame-like member. The invention also proposes modifications of the supporting handle.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an elevational view of a developing rack for direct positive photographs and the like constructed in accordance with this invention.

Fig. 2 is a side view of Fig. 1.

Fig. 3 is a horizontal sectional view taken on the line 3—3 of Fig. 1.

Fig. 4 is a bottom view looking in the direction of the line 4—4 of Fig. 2.

Fig. 5 is an elevational view of a developing rack for direct positive photographs constructed in accordance with another form of this invention.

Fig. 6 is a side view of Fig. 5.

Fig. 7 is an enlarged horizontal sectional view taken on the line 7—7 of Fig. 6.

Fig. 8 is a front elevational view of another developing rack constructed in accordance with still another form of this invention.

Fig. 9 is a side view of Fig. 8.

Fig. 10 is an enlarged horizontal sectional view taken on the line 10—10 of Fig. 9.

The developing rack for direct positive photographs, in accordance with that form of the invention disclosed in Figs. 1—4 inclusive, includes a frame-like member 10 having a plurality of groove-like passages 11 in which strips of photographs and the like indicated by the dot and dash lines 12, may be supported. This frame-like member 10 essentially consists of front and back walls 13 fixedly held in spaced positions by several side straps 14. The front and back walls 13 are constructed of a plurality of channel-like

2

members 15 which are alternately placed with their side walls directed rearwardly and forwardly and which are connected together in a rigid unit by soldering, brazing, welding or other method. The groove-like passages 11 comprise the opposed side walls of the inwardly directed channel-like members 15.

One end of the frame-like member 10 is closed for holding the photographic strips, indicated by 10 the dot and dash lines 12 from falling out. This closure means comprises strips 16 mounted across the bottom ends of the channels 15. A handle 17 is attached to the other end of the said frame-like member 10 and more specifically, upon the top end of one of the walls 13 thereof.

The operation of the developing rack consists merely in sliding a plurality of direct positive photographs and the like indicated by the dot and dash lines 12 in Fig. 2, into the groove-like 20 passages 11. The rack disclosed in the drawings is capable of receiving and holding six of these photographs. The rack may then be supported by the handle 17 and lowered into developing, fixing and washing fluids. A feature of the rack 25 construction resides in the fact that the person working on the photographs will not wet his hands. Moreover, the photographs will be suitably spaced from each other so that their emulsions do not stick together.

In Figs. 5—7 another form of the invention is disclosed which is very similar to the prior form, distinguishing merely in the details of construction. In this form of the invention the developing rack includes a frame-like member 20 having 30 a plurality of passages 21 in which strips of photographs, indicated by the dot and dash lines 22, may be engaged. The frame-like member 20 is formed from a plurality of parallel and spaced wire frames 23. These wire frames are held in 35 parallel spaced positions by spacer strips 24 attached to their sides.

The wire frames 23 have their side arms 23^a closer together than the width of the photographic strips 22 for forming the passages 21 in 45 which the photographic strips 22 may be engaged. At points, these side arms 23^a are formed with bellied-out sections 23^b. It is across these bellied-out sections 23^b that the spacer strips 24 are attached to the wire frames 23 for holding them 50 in relatively fixed positions. The purpose of the bellied-out portions 23^b is to permit the photographic strips 22 to pass in between the spacer strips 24.

The frame-like member 20 has one end closed 55 for supporting said strips of photographs. This end is closed by a strip 26 mounted across the bottom ends of the wire frames 23. A handle 27 is mounted on the other end of the frame-like member 20. More specifically, this handle 27 is formed from two wire sections. There is a hook section 28 which is attached upon a frame-like

section 29. These handles are attached upon the top end of the frame-like member 20, specifically, upon one side.

The developing rack is used in the identical fashion described relative to the first form of the invention. The photographic strips 22 are slipped into the groove-like passage 21, and then the rack is supported by the handle 27 and lowered in the respective fluids. The hook 28 may be used to hook the rack on a supporting object.

In Figs. 8-10 still another form of the invention is disclosed which is very similar to the prior form, distinguishing merely in the fact that additional wire frames may be added to produce additional passages, or wire frames may be taken away when they are not wanted. More specifically, this developing rack comprises a frame-like member 30 having a plurality of passages 31 in which strips of photographs 32 may be engaged. The frame-like member 30 is formed from a plurality of spaced wire frames 33. These wire frames 33 are held in spaced positions by bolts 34, upon which a plurality of spacer washers 40 are mounted. The bolts 34 are provided with nuts 41 for holding the spaced wire frames together as a unit.

Each of the wire frames 33 have side arms 33^a spaced together a distance less than the width of the photograph strips 32 so as to support the photographic strips along their side portions. Each of the side arms 33^a is formed with several bellied-out portions 33^b in the nature of loop portions through which the bolts 34 are engaged.

The bottom ends of the spaced wire frames 33 are formed with loop portions 33^c through which a bolt and nut 36 are mounted. This bolt and nut are provided with spacer washer 40 between the wire frames 33. The bolt and nut 36 close the bottom ends of the bottom passages 31.

A handle 37 is mounted upon the top of the frame-like member 30. This handle 37 includes a pair of hook portions 38 by which the rack may be hooked upon the side of a tank or other place. The handle 37 also includes a loop portion 39 which may be conveniently gripped. Preferably, the loop portion 39 is formed by continuing the adjacent wire frame 33 and twisting and forming it into shape. The hook portions 38 are soldered, welded or in any other way attached to the rack.

The dominating feature of this form of the invention resides in the fact that the nuts 41 may be removed and some of the wire frame 33 removed, or additional similar wire added for the purpose of changing the number of passages 31, which changes the number of photographs which the rack may accommodate. In other respects the operation of this form of the invention is identical to the previous forms.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A developing rack for direct positive photographs, comprising a frame-like member having a plurality of passages in which strips of photographs may be supported, means for closing one end of said member for holding said strips of photographs, and a handle mounted on the other end of said member, said frame-like member

comprising a plurality of parallel and spaced wire frames having sides spaced closer than the width of said photographic strips, said sides having bellied-out portions, fastening members engaged through and mounted on said bellied-out portions, and spacers for said frames mounted on said fastening members.

2. A developing rack for direct positive photographs, comprising a frame-like member having a plurality of passages in which strips of photographs may be supported, means for closing one end of said member for holding said strips of photographs, and a handle mounted on the other end of said member, said frame-like member comprising a plurality of parallel and spaced wire frames having sides spaced closer than the width of said photographic strips, said sides having bellied-out portions, fastening members engaged through and mounted on said bellied-out portions, and spacers for said frames mounted on said fastening members, said fastening members comprising bolts and nuts.

3. A developing rack for direct positive photographs, comprising a frame-like member having a plurality of passages in which strips of photographs may be supported, means for closing one end of said member for holding said strips of photographs, and a handle mounted on the other end of said member, said frame-like member comprising a plurality of parallel and spaced wire frames, the side arms of said wire frames being spaced closer than the width of said strips of photographs, said side arms having bellied-out portions forming loops, bolts and nuts engaged through said loops, and spacers mounted on said bolts for holding said wire frames in their spaced positions.

4. A developing rack for direct positive photographs, comprising a frame-like member having a plurality of passages in which strips of photographs may be supported, means for closing one end of said member for holding said strips of photographs, and a handle mounted on the other end of said member, said frame-like member comprising a plurality of parallel and spaced wire frames, the side arms of said wire frames being spaced closer than the width of said strips of photographs, said side arms having bellied-out portions forming loops, bolts and nuts engaged through said loops, and spacers mounted on said bolts for holding said wire frames in their spaced positions, the bottom ends of said wire frames having loops, and a bolt and nut engaged through said loop and comprising said means for closing one end of said member.

5. A developing rack for direct positive photographs, comprising a frame-like member having a plurality of passages in which strips of photographs may be supported, means for closing one end of said member for holding said strips of photographs, and a handle mounted on the other end of said member, said frame-like member comprising a plurality of parallel and spaced wire frames, the side arms of said wire frames being spaced closer than the width of said strips of photographs, said side arms having bellied-out portions forming loops, bolts and nuts engaged through said loops, and spacers mounted on said bolts for holding said wire frames in their spaced positions, the bottom ends of said wire frames having loops, and a bolt and nut engaged through said loop and comprising said means for closing one end of said member, said handle comprising hook portions and a loop portion.

HERMAN MILLMAN.
